UNITED STATES PATENT OFFICE.

ALFRED MARTIN, OF ROCKFORD, ILLINOIS, ASSIGNOR OF ONE-HALF TO
CHARLES E. THOMPSON, OF TRUMANSBURG, NEW YORK.

FILTER FOR CONDUCTOR-PIPES.

SPECIFICATION forming part of Letters Patent No. 617,032, dated January 3, 1899.

Application filed May 11, 1898. Serial No. 680,360. (No model.)

To all whom it may concern:

Be it known that I, ALFRED MARTIN, a citizen of the United States, residing at Rockford, in the county of Winnebago and State of Illinois, have invented certain new and useful Improvements in Filters for Conductor-Pipes, of which the following is a specification.

The object of this invention is to produce a filter to be attached to a conductor-pipe to prevent leaves and sediment from being carried with the rain-water into the cistern.

In the accompanying drawings, Figure 1 is a perspective view of the filter, a portion of the outer walls of which are broken away to show the interior thereof. Fig. 2 is a vertical central section through the filter.

Like letters of reference indicate corresponding parts throughout the both views.

20 A is the conductor-pipe.

B is the filter-chamber. B' and B² compose the rear wall thereof, B³ and B⁴ the side walls, and B⁵ is the front wall.

25 B⁶ is an inwardly-projecting ledge extending from the rear and sides of the filter-chamber, formed by turning inward the edges of the pieces B' and B² of the back and the pieces B³ and B⁴ of the sides of the chamber B at their adjacent edges and fastening these in-

30 turned edges together with solder or rivets.

B⁷ is a hinged door providing means for access to the interior of the filter-chamber B.

C is a wire screen.

35 D is a framework for the filter fabric. It rests upon the ledge B⁶ within the filter-chamber.

D' D² are filter-sacks stretched over the framework D. One alone may be used; but I prefer to employ two. These filter-sacks are

attached to the framework D by needle and 40 thread or in any other convenient way.

The wire screen C, the filter-sacks D' D², and the framework D are removable through the opening closed by the door B⁷.

In use this filter is connected with the conductor-pipe and the rain-water permitted to run through it on its way to the cistern. The sediment in the water is left in the filter-sacks D' and D², while leaves, sticks, &c., are caught by the wire screen C before reaching 50 the sacks D' D². To clean the filter, access is had to its interior through the hinged door B⁷, and the screen C and the filter-sacks D' D² may be thus removed for renewal or repair.

I claim as my invention—

1. In a water-filter for conductor-pipes, in combination, a filter-chamber having an inlet and an outlet, said chamber being formed with a two-piece side, the adjacent edges of the side being turned inward to form a supporting-ledge within the filter-chamber, a filter fabric in the chamber, and a supporting-frame for the fabric, substantially as and for the purpose specified.

2. In a water-filter for conductor-pipes, in combination, a filter-chamber having an inlet and an outlet, an opening in said chamber, a closure for said opening, said chamber being formed with a two-piece side the adjacent edges of which side are turned inward to 70 form a supporting-ledge within the filter-chamber, a filter fabric in the chamber, a supporting-frame for the fabric and a screen substantially as and for the purpose specified.

ALFRED MARTIN.
